UNITED STATES PATENT OFFICE

153,621

DESIGN FOR AN EDUCATIONAL GAME
BOARD

Sarah Anne Patterson, Edgewater, Colo.

Application April 7, 1947, Serial No. 138,204

Term of patent 14 years

(Cl. D25—1)

To all whom it may concern:

Be it known that I, Sarah Anne Patterson, a citizen of the United States, residing in Edgewater, county of Jefferson, and State of Colorado, have invented a new, original, and ornamental Design for an Educational Game Board, of which the following is a specification, reference being had to the accompanying drawing, forming part thereof.

In the drawing:

I claim:

The ornamental design for an educational game board, as shown.

SARAH ANNE PATTERSON.
